(57) **CLAIM**

The ornamental design for a E-wagon as shown and described.

DESCRIPTION

FIG. 1 is a perspective view of a E-wagon, showing my new design;

FIG. 2 is a front view thereof;

FIG. 3 is a rear view thereof;

FIG. 4 is a right side elevational view thereof;

FIG. 5 is a left side elevational view thereof;

FIG. 6 is a top plan thereof; and,

FIG. 7 is a bottom plan thereof.

The relatively lighter portions in FIGS. 6 & 7, bounded by broken lines, are for the purpose of illustrating portions of the E-wagon which form no part of the claimed design.

1 Claim, 7 Drawing Sheets
